(57) **CLAIM**

The ornamental design for a fairy orb, as shown and described.

DESCRIPTION

FIG. 1 is a perspective view from the top of the fairy orb showing my new design;

FIG. 2 is a perspective view from the bottom thereof;

FIG. 3 is a top view thereof;

FIG. 4 is a bottom view thereof;

FIG. 5 is a side view of a first quadrant thereof;

FIG. 6 is a side view of a second quadrant thereof;

FIG. 7 is a side view of a third quadrant thereof;

FIG. 8 is a side view of a fourth quadrant thereof;

FIG. 9 is a perspective view from the top of the fairy orb showing an alternative embodiment of the fairy orb shown in FIG. 1;

FIG. 10 is a perspective view from the bottom thereof;

FIG. 11 is a top view thereof;

FIG. 12 is a bottom view thereof;

FIG. 13 is a side view of a first quadrant thereof;

FIG. 14 is a side view of a second quadrant thereof;

FIG. 15 is a side view of a third quadrant thereof; and,

FIG. 16 is a side view of a fourth quadrant thereof.
